UNITED STATES PATENT OFFICE.

PHILIP H. POMEROY, OF BROOKLINE, MASSACHUSETTS.

TOY WHEEL.

1,124,654.

Specification of Letters Patent. Patented Jan. 12, 1915.

Application filed January 2, 1914. Serial No. 809,951.

To all whom it may concern:

Be it known that I, PHILIP H. POMEROY, a citizen of the United States, residing at Brookline, in the county of Norfolk and State of Massachusetts, have invented certain new and useful Improvements in Toy Wheels; and I do hereby declare the following to be a full, clear, and exact description of the invention, such as will enable others skilled in the art to which it appertains to make and use the same.

The present invention relates to an improvement in toy wheels.

The object of the invention is to produce a toy wheel adapted to be constructed from certain standard toy elements, and to this end the invention consists in the toy wheel hereinafter described and particularly defined in the claims.

In the accompanying drawings illustrating the preferred form of the invention, Figure 1 is a side elevation of the wheel; Fig. 2 is a sectional elevation of the same; Fig. 3 is a plan view of one of the hub parts; and Fig. 4 is a plan of an uncompleted peripheral band joint.

The illustrated embodiment of the invention is described as follows:

Two hub members 1 and 2 are associated together with their radial sockets 3 arranged at 45 degrees with relation to each other. These hub members 1 and 2 have flat central webs 4 provided at their centers with transverse holes 5. The radial spoke 35 embracing sockets 3 are open-ended and formed with one side in the plane of the web 4. Each web is provided with a keyway 6 which gives into the transverse hole 5. In a hub member having four spoke 40 sockets the keyway is arranged at an angle of 22½ degrees from the axis of one of the sockets. This construction of the hub members permits two of them to be associated together in interlocking position with their central holes and keyways in axial alignment and with the axes of the sockets of the two members lying in the same plane. The webs for the members thus associated form separated hub webs adapted to engage a 45 shaft received in the transverse hole at a distance apart equal to the diameter of the sockets. These two hub members may be secured to the shaft by a common pin by forcing it into the keyways 6 of the two 50 hubs. A pin should be selected which has a

size slightly greater than the depth of the keyways 6 so that when the pin is forced into the keyway, it is pressed against the shaft with some pressure and more or less deformed in the act of insertion by engagement with the hub webs and the shaft. The deformation of the pin and the pressure with which it is inserted are such as to cause the pin to hold the hub members on the shaft more or less rigidly, and, for the 60 purposes of the use to which the wheel is put, with sufficient strength to cause some power to be transmitted from the wheel to the shaft or from the shaft to the wheel. The sockets 3 receive the inner ends of the 70 spokes 7. The outer ends of the spokes are received in holes in the rim indicated in a general way by the reference character 8. The rim 8 has a channel section. The web 75 of the rim is provided with eight bosses 9 which are spaced 45 degrees apart and extend inward as shown, and have open-ended holes 10 therein to receive the outer ends of the spokes 7. The boss forms a slightly elongated portion to receive the outer ends 80 of the spokes and takes care of irregularities in the lengths of the spokes. The rim is discontinuous. The ends are not joined together except by the wheel band 11 which lies in the channel of the rim and holds the 85 rim together and prevents the spokes from movement radially outward through the holes in the rim.

In Fig. 4 is shown in detail the method of joining the ends of the band 11. One end 90 is provided with a tongue 12, the other with a hole 13 semi-circular in form through which the tongue 12 is passed. After the parts of the wheel are assembled, the wheel band 11 is laid in the channel and the 95 tongue 12 is passed through the hole 13, thus bringing the ends to the position shown in Fig. 4. Then the band is tightened and the end of the tongue is bent over, as shown in Fig. 1, to hold the band in place. 100

The hub members are construction units which are capable of being used in the construction of a wide variety of devices. The spokes are cut from wire and the rims may be supplied in endless lengths or cut and shaped to the size of the wheel to be made. The bands will be supplied in suitable lengths for the different sizes of wheels. It is to be observed that the wheel is easily assembled by the hands with the exception of 110

pulling the band tight around in the channel of the rim and that the only tool necessary for this purpose is a pair of pincers. The sockets and bosses may be pinched upon 5 the spoke ends, if desired. It is also to be noted that the invention, viewed in its broader aspects, contemplates a wheel whether constructed with one or two hub members, as a wheel of less rigidity and 10 strength can be constructed with one hub member and four spokes. Furthermore, it is to be observed that in the preferred form of wheel illustrated in the drawings in which two hub members are used, the two webs embrace the shaft 14 at separated points and thereby hold the pin in alignment with the shaft, as a result of which the wheel is secured to the shaft with greater security than if only one hub member were employed. 15 Furthermore, it is a feature of the invention that the portions of the hub which engage the pin by which the wheel is secured to the shaft are made of thin webs so that it is possible in forcing in the pin which secures the 20 hub to the shaft, to deform the wheel hub web members or the pin, or both, whereas if the hub were solid it would be impracticable with the fingers and ordinary hand tools to force the pin into the hole in the 25 keyway, because the resistance to the deformation by distortion or cutting of the metal of the parts would be so great as to prevent.

One feature of the invention resides in a 30 centrally webbed hub member provided with spoke sockets wherein the hole in the web is provided with a keyway located at an angle to the adjacent socket equal to one-fourth of the angle between successive 35 sockets, so that the keyway of two associated hub members will come midway between two sockets, the one a socket of the one hub member and the other a socket of the other hub member.

40 45 The hub member is not claimed broadly herein.

The present invention is not limited to the 50 illustrated embodiment as it may be embodied in other forms within the scope of the following claims.

I claim—

- 55 1. A toy wheel consisting of a hub member having open-ended radial spoke sockets and a central transverse hole, a rim provided with open-ended spoke holes, spokes received in the sockets and rim holes connecting the hub member and rim, and a band embracing the spoke ends to hold the parts of the wheel together, substantially as described.
- 60 65 2. A toy wheel consisting of a single sheet metal hub member having radial spoke-embracing sockets and a central transverse hole, spokes supported in the sockets, and a rim having holes for receiving the ends of the spokes, substantially as described.

3. A toy wheel consisting of a hub having two hub members each provided with a transverse hole and radial sockets, the sockets interlocking with each other, spokes supported in the sockets, a rim having holes for receiving the ends of the spokes, and means for holding the spokes in place, substantially as described. 70

4. A toy wheel consisting of a hub member having open-ended radial spoke-embracing sockets and a central transverse hole, spokes supported in the sockets, a rim having holes for receiving the ends of the spokes, and means for holding the hub, spokes and rim together, substantially as 75 described. 80

5. A toy wheel comprising a sheet metal hub member having open-ended radial spoke sockets and a central transverse hole, a channel rim provided with spoke holes, spokes received in the sockets and rim holes for connecting the hub member and rim, and means for holding the hub, spokes and rim together, substantially as described. 85

6. A toy wheel consisting of a hub member having radial spoke sockets and a central transverse hole, a channel rim member provided with spoke holes, spokes received in the sockets and rim holes connecting the hub member and rim, and a band located in 90 the rim channel and embracing the spoke ends to hold the parts of the wheel together, substantially as described. 95

7. A toy wheel consisting of a sheet metal hub member having radial spoke-embracing 100 sockets and a central transverse hole, a sheet-metal channel rim having hollow inwardly projecting bosses in the channel web for receiving the ends of the spokes, spokes supported in the sockets and rim bosses, and 105 means for holding the hub, spokes and rim together, substantially as described.

8. A toy wheel having a hub consisting of two hub members having central webs provided with central holes having keyways 110 giving into the holes, such keyways being so located with respect to the spoke sockets that when the two hub members are associated in interlocking position with the spoke sockets of the one hub member arranged at 45 degrees with relation to the spoke sockets of the other hub member the keyways are in alignment, spokes supported in the spoke sockets and a rim carried by the spokes, substantially as described. 115 120

9. A toy wheel having a hub consisting of two hub members each of which has four radial spoke sockets arranged at right angles to each other and a central socket supporting web provided with a central hole 125 and a keyway giving into the hole located at an angle of 22½ degrees from the axis of a socket, spokes supported in the sockets, and a rim, substantially as described.

10. A hub member for toy wheels con- 130

sisting of a central flat thin web having four radial spoke sockets supported by the central web and arranged at right angles to each other, said web having a central hole provided with a keyway located at an angle of 22 $\frac{1}{2}$ degrees to the axis of a socket, substantially as described.

11. A hub member for toy wheels having a central web provided with a plurality of spoke sockets radially supported on the web and a central hole in the web provided with a keyway, said keyway being located at an angle to an adjacent socket equal to one-fourth of the angle between two successive sockets, substantially as described.

12. A hub for toy wheels consisting of two hub members each having a web provided with a central hole and spoke sockets radially supported thereon, said sockets being located with one side in the plane of the web so that when the hub members are associated together in interlocking position the webs afford separated shaft-engaging portions, so as thereby to support the hub rigidly on the shaft, substantially as described.

13. A toy wheel having a round shaft and two thin separated shaft engaging webs provided with alined round central holes fitting the round shaft said webs having alined key ways giving into the central hole.

14. A toy wheel consisting of a sheet metal hub member having radial spoke sockets formed so that one side of each socket lies in the same plane with the hub and the axes of the sockets lie outside the plane of the hub, spokes carried by the

sockets, and a rim engaging the outer ends of the spokes, substantially as described.

15. A toy wheel consisting of a sheet metal hub member having a central transverse hole and radial sockets whose axes lie in a plane outside of and parallel to the plane of the hub, spokes supported in the sockets, and a rim having holes for receiving the ends of the spokes, substantially as described.

16. A toy wheel consisting of two hub members each having a central web supporting a plurality of sockets adapted to receive spokes, one side of said sockets being in the same plane with the web, said hub members being so positioned that the axes of the sockets lie in the same plane, spokes in said sockets, a rim provided with holes to receive the outer end of said spokes, and a band embracing said rim, substantially as described.

17. A toy wheel consisting of a hub comprising two centrally-webbed hub members supporting radial spoke sockets arranged so that the sockets of one hub member are disposed between the sockets of the other, the axes of the sockets lying in a plane parallel to and outside of the planes of the hub members, spokes in the sockets, a rim engaging the outer ends of the spokes, and means for holding the spokes in place, substantially as described.
